UNITED STATES PATENT OFFICE.

HEREWARD LESTER COOKE, OF PRINCETON, NEW JERSEY, ASSIGNOR TO COOKE PATENTS INCORPORATED, OF NEW YORK, N. Y., A CORPORATION OF DELAWARE.

LIGHT-PROJECTING DEVICE.

Application filed May 3, 1921. Serial No. 466,487.

This invention relates to light projecting devices and has for its primary object to provide a device of the above mentioned character in which the source of light proper 5 is fixed at a definite point, such as the focal point, relative to the reflector or other device for projecting the light.

This is not true of the devices heretofore usual, particularly such as employ incandescent 10 electric lamps as sources of light, because the filaments of different lamps are not at exactly the same position relatively to the sockets, so that as the various lamps are placed into the sockets, the direction of the beam 15 of light changes. In many instances, however, it is exceedingly important that the direction of the beam remain unchanged, as for example, in railway signaling and in automobile headlights, in which latter instance 20 the beam should be directed to the ground and not exceed a definite elevation in order to prevent glare.

In the present invention I propose to fix the filament absolutely in position relatively 25 to the reflector and in the particular embodiment of the invention hereinafter described, I propose to employ part of the bulb surface itself as a reflector, this part of the surface being shaped substantially like a paraboloid 30 at the focus of which is placed the lamp filament or other source of light. I propose furthermore to provide inside the bulb a shield which serves to permit only the reflected light to pass out of the bulb. This 35 shield may, however, be made of colored or translucent rather than opaque substance so as to permit part of the direct rays to pass therethrough and out of the bulb. This light, however, is so reduced in intensity as to prevent 40 glare.

A good understanding of the invention may be had from the following description of certain specific forms of the embodiment thereof, reference being had to the accompanying drawing, in which:

Fig. 1 is a view partly in section, showing one form of embodiment of the invention;

Fig. 2 is a view similar to Fig. 1, showing 50 a modification thereof;

Figs. 3 and 4 are views showing another modification, Fig. 3 being a side, and Fig. 4 a front elevation thereof; and

Figs. 5 and 6 are views showing still another modification of the invention, Fig. 5

being a longitudinal section, and Fig. 6 an end elevation.

Similar characters of reference designate similar parts in each of the several views.

The lamp illustrated in Fig. 1 comprises 60 a bulb 1, which is mounted in a base 2 which is arranged to cooperate with a bayonet socket of the type well known in the art. Obviously, any other type of base and socket may be employed. The rear wall *a* of the 65 lamp is in the shape of a paraboloid, and the filament 3 is carried on a filament support 4 having such length and position that the center of the filament is at the focal point 70 of the paraboloid. This filament is as compact as possible, and may be of any known kind, which approximates the ideal condition of a point source of light. The interior or exterior surface of portion *a* is silvered, and serves, therefore, to reflect the rays of light 75 from source 3 and to form them into a substantially parallel beam of light which passes through the non-silvered part *b* of the bulb. A shield 5 of opaque substance is shown 80 mounted in the interior of the bulb where it is supported by means of wires 6 extending from the filament support 4. The shield is illustrated as being substantially convex in shape and of such size as to prevent direct rays of light from passing out of the bulb, 85 so that only the parallel beam of reflected light is emitted therefrom. If desired, the shade 5 may be made of colored or other translucent material so as to permit the direct rays of light to pass out of the bulb 90 after they have been so reduced in intensity that they will cause no glare.

The lamp illustrated in Fig. 2 is similar to that of Fig. 1 except that the base is at right angles to the axis of the bulb. In this modification, a filament support 4' extends through a cylindrical recess 7 in the reflecting portion *a'* of the lamp bulb. Shield 5', moreover, is directly mounted on the filament support 4'.

Figs. 3 and 4 show the invention in its preferred form of embodiment. In this modification the filament support 4'' is shown in a horizontal axial position, extending into the bulb from the forward or transparent portion *b''* of the bulb. A shield 5'' is shown as being integral with the support 4'', the surface 10 of the support being for this purpose coated with opaque or colored paint although any other suitable method may be em- 110

ployed for rendering the shield opaque or translucent. The reflecting surface α'' of the bulb is shown as provided with an enlargement 11 preferably unsilvered, which serves 5 primarily for increasing the heat radiating capacity. The base of the bulb is mounted in a socket carried on an arm 15 which is pivoted on the bolt or rivet 16 and passes between the members 17 which are parts of the 10 frame in which the lamp is supported. The lower end of the arm 15 is bevelled, as shown, and co-acts with a blade spring 18 which serves to bias the same in counterclockwise direction. A stop 19 limits the extent of movement 15 of arm 15 and a screw 20 is provided on arm 15 to cooperate with the stop. By means of this arrangement, the elevation or depression of the beam of light emitted from the lamp may be adjusted closely. This feature 20 is particularly valuable when the lamp is used on automobiles or other vehicles, where it is important that the beam shall not exceed a given height, so as to prevent obnoxious glare.

25 When a filament of the lamp burns out, a new lamp may be conveniently mounted in the socket by swinging the arm 15 downwardly against the pressure of spring 18 until the bevelled portion of the arm engages 30 the surface 21 of members 17, at which time the arm is substantially horizontal so that the whole lamp may be conveniently removed and a new one substituted therefor.

It will be understood that the lamp and 35 its mounting, as illustrated in Figs. 3 and 4, is preferably enclosed in a casing having a removable front which may be of plain glass. The casing serves to protect the lamp from breakage and from dirt, and is of particular 40 importance when the lamp is used as a head light for an automobile or other vehicle.

It will be observed that although part of the light is obscured, owing to the mounting being placed in the front of the lamp, the 45 practical effect of this is negligible, owing to the intensity of the light.

In manufacturing the lamps, the bulbs are preferably blown in moulds shaped in accordance with the distribution of light to be 50 derived from the lamp α , and the filaments are thereupon centered relatively to the focal points of the reflecting portions of the bulbs. In place of the filament type of lamps it is possible to use lamps employing other sources 55 of light, as for example, the enclosed tungsten-arc lamp, which is particularly suitable for certain applications, owing to the concentration of the light at a single point. Although the reflecting surfaces have heretofore 60 been described as being paraboloids, it will be readily understood that other suitable shapes may be employed, as for example, a shape which will cause the beam to spread in a lateral direction so that when the lamp is 65 used as a head light, the beam is spread over

a wide area of the road. It will be understood that the proper shape suitable for any particular purpose may readily be designed by graphical methods in accordance with the well-known laws of optics. An important 70 advantage of this method of making the lamps is that any shape may be readily and accurately reproduced by using properly shaped moulds.

Although in each of the above-described 75 embodiments of the invention a shield is mounted inside the bulb, it is to be understood that this shield may be omitted, if desired. Such an embodiment of the invention is illustrated in Figs. 5 and 6, where 30 is 80 the lamp provided with a paraboloid reflecting surface α at the focus of which is mounted the filament 3. The lamp is mounted in a socket 31 fixed in the rear end of a sheet metal casing 32. The interior surface of this casing is painted preferably a dead black so as to be substantially non-reflecting. Across the forward end of the casing is placed a shield 33 of opaque, colored or translucent material, the lower edge of which is in substantially 90 horizontal alignment with the filament, as indicated by the line 34, so that no direct rays of light emanating from the filament can pass above the horizontal plane. The reflected rays, moreover, are substantially 95 parallel and tilted downwardly, owing to the slight inclination which is given to the lamp 30. The result of this is that no light passes above the horizontal so that there can be no glare above the level of the lamps. When, 100 therefore, the lamps are used as the headlights of an automobile or other vehicle, the road will be intensely illuminated but all glare will be avoided. The marked advantage which this form of embodiment of the 105 invention in common with other forms, has over the headlights now common in the art, is the absolute fixedness of the filament relatively to the reflecting surface, so that the reflected beam of light has a fixed form of 110 cross-section, which does not vary, owing to the impossibility of moving the filament relatively to the reflecting surface. This fixedness does not exist in the present headlights and the light emitted by them will consequently 115 vary in direction, thus producing glare in spite of all other precautions.

Another advantage which the projecting device of my invention has over those now 120 common in the art, particularly the type in which a separate reflector is mounted behind a lamp bulb, is the absence of a multiplicity of reflecting and refracting surfaces, such as the inner and outer surfaces of the lamp bulb, by which surfaces part of the light 125 is reflected and refracted a number of times before it can pass out of the headlight, with the result that the beam loses its intensity and sharp definition. In the projecting lamp of my invention, there is but one reflecting 130

surface, particularly, if the silvering is applied to the inner surface of the bulb, so that little or nothing of the above-described effect is entailed.

5 While I have illustrated and described my invention in connection with only a few preferred embodiments thereof, it will be understood that I do not intend to limit myself to these specific embodiments shown, but that 10 I intend to cover my invention broadly in whatever form its principle may be employed.

What I claim is:

1. In a lamp, a glass bulb having a rearward part of its surface in the shape of a 15 paraboloid, a concentrated source of light comprising a filament located within said bulb substantially at the focus of the said paraboloid, means for rendering the said parabolic portion of the surface of the bulb 20 reflective to the light from said filament, the remaining surface of the bulb permitting the light to pass freely out of the bulb, a support for said filament, a base in which said support is mounted, said support and base being disposed forwardly of said reflecting surface, and serving as a shield for the rays 25 passing directly from said filament source.

2. In a lamp, a glass bulb, a concentrated source of light located within said bulb, said 30 bulb having a portion of its surface treated to reflect light from said source, and a shield interior to said bulb for preventing the direct rays of light from passing out of said bulb.

3. In a lamp, a glass bulb, a concentrated source of light located within said bulb, said bulb having a portion of its surface treated to reflect light from said source, and a shield 40 interior to the bulb located in the path of the rays passing direct from the filament to the exterior of the bulb, but not in the path of the reflected rays passing out of the bulb.

4. In a lamp, a bulb having rear reflecting and front transparent surfaces, a source 45 of light within said bulb, and means interior to the bulb for intercepting the path of the direct rays substantially coaxial to the bulb without intercepting the path of a substantial part of the rays passing from the reflector to the exterior of the bulb.

5. In combination, a bulb consisting of reflecting and transparent portions, the said transparent portion extending across substantially the entire front of the bulb, a 55 source of light and a shield interior to the bulb said shield being constructed so as to intercept rays of light coaxial to the bulb, said reflecting portion of the bulb, the source of light and the shield being so placed with reference to each other, that substantially 60 no direct light passes out of the bulb.

6. A lamp comprising a bulb, said bulb

comprising a rearward reflecting and a forward transparent surface, a concentrated source of light within said bulb, and a shield 65 interior to said bulb for permitting the direct rays of light to fall on substantially the entire reflecting surface and for preventing substantially all the direct rays from being emitted. 70

7. A lamp comprising a bulb, a concentrated source of light within said bulb, a portion of said bulb being arranged to reflect the light from said source in a beam of predetermined direction and a shield 75 mounted inside said bulb for eliminating substantially all of the light passing directly from said source in the direction of said beam.

8. In combination, a bulb having part of 80 its surface in the shape of a paraboloid; a concentrated filament within said bulb, said filament being located at the focus of said paraboloid, and a stationary shield interior to the bulb for materially reducing all light 85 directly emitted from said filament, except such as is reflected from said paraboloid surface.

9. In a unitary lamp structure, a reflector, 90 a concentrated source of light and means interior to the bulb for eliminating substantially all the centrally direct rays from the source and yet permitting the emission of a beam of indirect light substantially parallel to the axis of the reflector of said lamp. 95

10. In a unitary lamp structure, a bulb, a concentrated source of light therein, a reflector integral with the bulb, a stationary shield interior to the bulb and directly in front of the filament and being of such a 100 form that it intercepts the centrally direct rays of the lamp but permits the remainder of the light to distribute itself uniformly over substantially the entire reflector.

11. In a lamp, a glass bulb having a rearward part of its surface in the shape of a paraboloid, a concentrated source of light comprising a filament located within said bulb substantially at the focus of the said paraboloid, whereby said rays emerge from 110 the bulb substantially parallel, means for rendering the said parabolic portion of the surface of the bulb reflective to the light from said filament, the remaining surface of the bulb permitting the light to pass freely 115 out of the bulb, a support for said filament, said support being integral with said reflecting surface whereby said filament and surface are immovably fixed with reference to one another. 120

In testimony whereof I have affixed my signature to this specification.

HEREWARD LESTER COOKE.
